UNITED STATES PATENT OFFICE.

JAMES W. KENNEDY, OF CANTON, OHIO.

ICE-CREAM-CONE DISPENSER.

1,218,186.

Specification of Letters Patent. Patented Mar. 6, 1917.

Application filed September 1, 1916. Serial No. 118,033.

To all whom it may concern:

Be it known that I, JAMES W. KENNEDY, a citizen of the United States, residing at Canton, in the county of Stark and State 5 of Ohio, have invented a new and useful Ice-Cream-Cone Dispenser, of which the following is a specification.

The present invention primarily has to do with ice cream cone dispensers, and in connection therewith the shipping or handling of the cones. It is well understood that ice cream cones are of a brittle nature, easily broken or injured by improper handling and shipping. It is also well understood that 10 ice cream cones are easily contaminated by indiscreet handling and it is of importance to provide means for distributing ice cream cones properly packed and so packed that they can be readily placed in position to be 15 removed by the retailer as occasion requires or in other words to be placed in the dispensing device without handling the individual cones.

The above purposes and objects I attain 20 by the construction illustrated in the accompanying drawings, although my invention may be embodied in a variety of other mechanical forms, the construction illustrated being chosen by way of example.

30 In the accompanying drawing:

Figure 1 is a longitudinal section.

Fig. 2 is a section on line 2-2, Fig. 1.

Fig. 3 is a section on line 3-3, Fig. 1.

Fig. 4 is an elevation of the combined 35 magazine and shipping tube.

Fig. 5 is an enlarged view of the inner and outer bands showing the supporting socket properly connected.

Similar numerals of reference indicate 40 corresponding parts throughout all the figures of the drawings.

In the accompanying drawing 1 represents the magazine, which also serves the purpose of a shipping tube. This tube is 45 preferably made of thin sheet metal of sufficient thickness to give the proper rigidity, but it is obvious that other suitable material can be used as the only object is to provide a magazine and shipping tube that will be 50 light. In ice cream cone dispensers it is necessary to form the magazine of considerable length, especially where a large number of cones are placed in the magazine and hence it is of importance to form the magazine of 55 light material so that the same can be handled easily and at the same time conven-

iently shipped from place to place. When the magazine 1 is used as a shipping tube its ends should be provided with the caps 2, which are of the ordinary construction, the 60 cones being preferably placed in the tubes after the same are properly formed and baked and can then be shipped to various places for use and places where the ice cream and the cones are sold at retail. 65

For the purpose of providing means for seeing the contents of the magazine or tube 1 from time to time it is preferably provided with a window or transparent opening, the transparency being preferably formed of 70 mica 3 and the mica held in position by means of the binding strip 4. The specific manner of connecting the transparent material is immaterial and any well known means may be employed, but I consider the 75 binding strip the preferable way.

For the purpose of supporting the magazine 1 in a vertical position when in use as a part of the dispensing device the band or collar 5 is provided, which band or collar is 80 formed of sufficient width to properly hold the tube 1 and at the same time to provide means for properly holding the removable cup 6, which removable cup is inserted in the bottom or lower end of the band or collar 5 as best illustrated in Fig. 1. An outer band 7 is located concentrically with the collar 5, but is formed of a diameter somewhat greater than the diameter of said collar, in order to provide means for inserting the 85 magazine 1 between said outer and inner bands 5 and 7. To the bands 5 and 7 is attached the socket bracket 8 by means of the rivets 9 or their equivalents. The socket bracket 8 is made up of the plate portion and the screw threaded socket 10 and, for the 90 purpose of supporting the magazine the plate is provided with the shoulder 11 which forms a stop for the magazine tube 1. 95

The screw threaded socket 10 is for the 100 purpose of receiving the screw threaded end 12 of the supporting arm 13, to which supporting arm is attached a connecting plate 14. It will be understood that owing to the fact that the magazine must be formed of 105 considerable length in order to hold the desired number of cones and for convenience in manipulating the magazine from time to time, either for loading the magazine with cones or for any other purpose provision should be made for turning the magazine 110 into a horizontal position, and for this pur-

pose the screw threaded socket 10 and the screw threaded portion 12 of the arm 13 is provided, by means of which a swivel connection is provided. It will be understood that some means should be provided for limiting the pivotal movement of the magazine, as only practically a quarter of a turn is necessary to bring said magazine into said position and in order to provide means for so limiting the pivotal movement the collar 15 is connected to the arm 13 in any convenient and well known manner, which forms a stop when the outer end of the screw threaded socket strikes said collar. For the purpose of properly guiding the cones as they descend into the cup 6 from time to time the guide bars 16 are provided, which guide bars are connected at their bottom or lower ends to the cup 6 and extend to the top or upper portion of said cup.

To the collar or band 5 are attached any desired number of spring arms 17, which spring arms extend upward and preferably a short distance above the top of the ring 5 and are for the purpose of retaining the column of cones when the cup 6 and the lowermost cone are removed. The spring arms 17 will be pressed outward when the cup 6 is placed in the position shown in Fig. 1, thereby bringing the top or upper ends out of contact with the cone; but when the cup 6 is removed the top or upper ends of the spring arms 17 will automatically move inwardly a short distance and a sufficient distance to prevent the downward movement of the column of cones.

When the cone contained in the cup 6 has been removed and the cup again placed in position, the spring arms 17 will be forced outwardly, thereby releasing the column of cones and permitting the lowermost cone of the column to drop into the cup 6 when the same may be removed as above described.

For the purpose of insuring the withdrawal of the cone contained in the cup when the cup 6 is removed, the pointed bar or pin 18 is provided, which is normally held out of contact with the cone by means of the spring 19 and the headed shank 20. When it is desired to remove the cup the headed shank 20 is pushed inwardly and preferably held by the finger or thumb, while the cup is removed and when the pointed pin or bar 18 is pushed inward its point will be inserted into the cone a sufficient distance to insure its withdrawal, but upon releasing the spring the pin or bar 18 will automatically move outwardly, thereby leaving the cone free to be taken out of the cup.

The top or upper end of the magazine 1 is provided with the cap or cover 21, which cap or cover is placed upon the top or upper end in the usual way. To one side of

the cap or cover 21 are attached the spaced arms 22, said spaced arms being for the purpose hereinafter described. To the connecting block 23 or its equivalent is attached or formed integral therewith the bar 24, to which bar is attached the spring 25, to the free end of which is attached the cross head 26, which head is for the purpose of engaging the spaced arms 22 and preventing any accidental displacement or turning of the magazine 1. I prefer to curve the spaced arms 22, so that they will act as a guide to the cross head 26.

For the purpose of convenience the chain 27 should be attached to the free end of the spring 25 by means of the arm 28 or its equivalent so that a pull upon the chain 27 will move the free end of the spring 25 downward, thereby disengaging the same from the spaced arms 22, at which time the magazine is free to be turned upon the supporting arm 23. It will be understood that the spring 25 should be formed of sufficient rigidity to prevent any accidental movement of the magazine; but of sufficient elasticity to allow the same to be brought out of the way of the arms 22 by means of the pull chain 27 or its equivalent.

It will be understood that before placing the cap or cover 21 in the position shown in Fig. 1 and also placing the cup 6 in position to receive and hold the lowermost cone, the caps 21 must be removed from the magazine, owing to the fact that when the caps 21 are placed in position to close the ends of the magazine it performs the function of a shipping tube, but also constitutes the magazine.

Having fully described my invention, what I claim as new and desire to secure by Letters Patent, is—

1. In a dispensing device of the class described, the combination of a magazine, a cone receiving cup detachably connected to said magazine, a series of spring cone retaining arms secured to the magazine and means carried by the cup adapted to pierce the body of the cone and means for holding the cone piercing means out of normal engagement.

2. In a dispensing device of the class described, the combination of a magazine, a cone receiving cup detachably connected to said magazine, and provided with cone guiding bars, a series of spring cone retaining arms secured to the magazine and means carried by the cup adapted to pierce the body of the cone and means for holding the cone piercing means out of normal engagement.

3. In a dispensing device of the character described, the combination of a magazine, a cone receiving cup detachably connected to said magazine, means carried by the magazine to support a column of cones, con-

centric bands secured to the magazine and spaced from each other, a bracket secured to the outer band, said bracket provided with a socket, a supporting arm located in the socket and means for normally holding the magazine in vertical position.

- 5 4. In a dispensing device of the character described, the combination of a magazine provided with a transparent opening, a cone receiving cup detachably connected to said magazine, spring arms connected to the magazine, said spring arms adapted for engagement with a cone and means for supporting the magazine.
- 10 5. In a dispensing device of the character described, the combination of a magazine, said magazine provided with means for supporting a column of cones, a cone receiving cup detachably connected to the magazine,
- 15 20 a cover secured to the top or upper end of the magazine, said cover provided with spaced arms, a spring arm provided with a

cross head, said spring arm adapted to be located between the spaced arms secured to the cover.

25

6. In a dispensing device of the character described, the combination of a cone holding magazine, a detachable cup provided with a pointed pin adapted for engagement with the cone contained in the cup and means for holding the pin out of engagement with the cone.

30

7. In a dispensing device of the character described, the combination of a magazine, means for pivotally mounting said magazine and means for limiting its pivotal movement, a cone receiving cup detachably connected to the magazine and means carried by the magazine adapted to support a column of cones.

35

In testimony that I claim the above, I have hereunto subscribed my name.

40

JAMES W. KENNEDY.
